UNITED STATES PATENT OFFICE

BENJAMIN ROTHBLUM, OF NEW YORK, N. Y.

GARMENT

Application filed November 18, 1931. Serial No. 575,794.

This invention relates to garments, and particularly to such as may be used as bathing suits. The principal object is to provide such garment with means whereby it may be readily, rapidly, and conveniently converted to either expose substantially the entire back of the wearer to the invigorating and health imparting action of the sun's rays or to maintain the back of the wearer covered up for comfort, warmth, and protection.

Other objects and advantages will herein-after appear.

In the accompanying drawing,—

Fig. 1 is a general perspective view of the garment of this invention, showing the back thereof as it appears when in operative state or when covering up the body.

Fig. 2 is a perspective view of the front of the garment showing it as it appears when the back portion is in inoperative state or when exposing the back of the wearer.

Fig. 3 is a rear elevation of the garment, in a reduced scale, showing it as it appears when converted to expose the back of the wearer.

Fig. 4 is a perspective view of a garment, in the same scale as Fig. 3, showing a modification of the invention.

The garment 1, made of any suitable material, comprises a waist portion 2 forming part of a usual body portion 3, and a chest portion 4. Said chest portion is configurated to form a pair of portions 5, 6 that are normally strung over the shoulders of the wearer, as shown. The portion 5 broadens out into a sheet 7 of roughly triangular configuration that covers the back of the wearer, one side of which sheet merges with the chest portion 4, another side extends along the rear of the waist portion 2, and the third side extends diagonally from the shoulder to the oppositely situated side of the waist portion, where at the sheet 7 is configurated into a belt portion 8 that passes through a slit 9 of the waist portion and extends toward the front of the waist portion. The shoulder portion 6 broadens out into a similar sheet 10 that covers the back of the wearer and overlaps the sheet 7, and is provided with a similar belt portion 11 that extends to the front of the waist portion, whereat the two belt por-

tions 8, 11 may be tied together to support the back portions 7, 10 in the position shown in Fig. 1. In the centre of the rear of the waist portion 2 is located a button 12, to which may be fastened both of the back portions 7, 10 by means of registering button-holes 13 of the latter, to secure said back portions firmly to the waist portion.

When it is desired to wear the garment with its back portions 7, 10 in operative condition for covering up the wearer's back, therefore, the said portions may be covered over the back by threading the belt 8 through the slit 9, lapping the portion 10 over the portion 7, securing both of said portions to the button 12, and then tying the two belts 8, 11 together in front, in the manner shown in Fig. 1, thereby efficiently supporting the back portions 7, 10 as indicated. When it is desired to convert the garment to expose the wearer's back to the sun's rays, the belts 8, 11 may be united, the belt 8 threaded out of the slit 9, and the back portions 7, 10 may be then folded about the shoulder portions 5, 6 over and upon the sides of the wearer in the manner illustrated in Figs. 2, 3, whereupon the meeting belts 8, 11 may be tied together in the manner shown in Fig. 1 to efficiently support the inoperative back portions 7, 10 in their present positions.

According to the modification shown in Fig. 4, the rear of the waist portion is provided with buttons 14, 15, and the back portions 7, 10 are not equipped with any belt portions, but have button-holes 14a, 15a adapted to register with and fasten to the buttons 14, 15 respectively. When it is desired to wear the garment with its back portions 7, 10 in operative condition for covering up the wearer's back, the back portion 7 is secured in place by fastening its button-holes 14a, 15a to the buttons 14, 15, and then the back portion 10 is lapped over the portion 7 and its corresponding button-holes are secured to the same buttons. When it is desired to convert the garment to expose the wearer's back, both portions 7, 10 are unbuttoned and folded about the shoulder portions, over and against the sides of the wearer toward the front, and then the corners of the back por-

tions 7, 10 may be fastened to the garment by the button-holes 14a securing to a pair of buttons 16, to thereby efficiently support the inoperative back portions in their present positions.

Variations may be resorted to within the scope of the invention.

Having thus described my invention, I claim:

10. 1. A garment including a chest portion and waist portion, said chest portion having a pair of shoulder support portions, one of said shoulder support portions forming into a back portion and terminating in a securing means, the other of said shoulder support portions forming into a back portion that overlaps said former back portion and terminates in a securing means, means for fastening said back portions to the rear of said 15 waist portion, said back portions being adapted to fold over forwardly toward the front of the wearer to expose their reverse sides and the wearer's back, and said back portions being held by said securing means 20 while in position to cover the wearer's back and when in position to expose the wearer's back.
2. A garment including a chest portion and waist portion, said chest portion having a 25 pair of shoulder support portions, one of said shoulder support portions forming into a back portion and terminating in a belt portion, the other of said shoulder support portions forming into a back portion that overlaps said former back portion and terminates in a belt portion, means for fastening said 30 back portions to the rear of said waist portion, said latter back portion having an opening, the belt of said former back portion 35 passing through said opening, said belt portions extending to the front of said waist portion for tying thereat for supporting said back portions while covering the wearer's back, said back portions being adapted to 40 fold over forwardly toward the front of the wearer to expose their reverse sides and the wearer's back, and said belt portions being adapted to again tie at the front of said waist portion for supporting said back portions to 45 maintain them in the latter position.

50. 3. A garment including a chest portion and waist portion, said chest portion having a pair of shoulder support portions, one of said shoulder support portions forming into a back portion and terminating in a securing means, the other of said shoulder support portions forming into a back portion that overlaps said former back portion and terminates in a securing means, means for fastening said back portions to the rear of said 55 waist portion, said back portions being adapted to fold over forwardly toward the front of the wearer to expose their reverse sides and the wearer's back, and said back

portions being held by said securing means while in position to expose the wearer's back.

Signed at New York, in the county of New York, and State of New York, this 16th day of November, A. D. 1931.

BENJAMIN ROTHBLUM.
